UNITED STATES PATENT OFFICE.

JULIUS T. DE SOUCHET, OF CHICAGO, ILLINOIS, ASSIGNOR TO THE RAILROAD SUPPLY COMPANY, OF CHICAGO, ILLINOIS, A CORPORATION OF ILLINOIS.

TIE-PLATE.

No. 821,343.

Specification of Letters Patent. Patented May 22, 1906.

Application filed August 17, 1904. Serial No. 221,009.

To all whom it may concern:

Be it known that I, JULIUS T. DE SOUCHET, a citizen of the United States, residing at Chicago, in the county of Cook and State of Illinois, have invented certain new and useful Improvements in Tie-Plates, of which the following is a full, clear, and exact specification.

This invention relates to improvements in tie-plates interposed between railroad-rails and their supporting-ties, the rails being held down and against lateral movement by spikes driven through openings in the tie-plates and the tie-plates provided with flanges or ribs so arranged that when driven into the tie they expose the resulting broken-down fibers to saturation by water from rain and other causes, rotting and deteriorating the tie and correspondingly weakening and reducing its stability so quickly and to such an extent as to permit an objectionable shifting movement of the tie-plates and require the turning of a tie before it is otherwise injured in order that a sound surface may be presented to the tie-plate, all of which is not only objectionably expensive in time, but in money.

The object of my invention is a tie-plate so constructed that the lateral movement of railroad-rails held down by spikes is substantially, if not entirely, resisted by the tie-plate and that the fibers broken down by the flanges or ribs on the tie-plate shall not be exposed to water or other elements tending to rot the fibers or reduce the stability of the tie-plate when in its operative position on the tie.

With these ends in view my invention consists in certain features of novelty in the construction, combination, and arrangement of parts by which the said objects and certain other objects hereinafter appearing are attained, all as fully described with reference to the accompanying drawings and more particularly pointed out in the claim.

In the said drawings, Figure 1 is a perspective view of a tie-plate embodying my invention with a part thereof broken away to illustrate the construction by which fibers broken down by the ribs or flanges are isolated from moisture and with a portion of the rail in its operative position on the tie-plate against the abutment thereof. Fig. 2 is a longitudinal section of Fig. 1 on a line longitudinally of the tie-plate and centrally through the rib thereof. Fig. 3 is a transverse section on the

line 3 3, Fig. 2. Fig. 4 is a transverse section of a modified form of the tie-plate shown in the preceding figures; and Fig. 5 is a perspective view of the under side of a tie-plate narrower than the tie and provided with flanges and a rib deppresible therein and embodying one feature of my invention.

Similar numerals of reference indicate the same parts in the several figures of the drawings.

1 indicates an ordinary wood tie having mounted thereon a tie-plate 2 of the usual length, but of such width that its side flanges 3 may overlap and embrace the opposing sides of the tie, as distinguished from a tie-plate narrower in width and having its side flanges forced into the fibers of the tie. The flanges 3 when embracing the opposing sides of the tie preferably extend the entire length of the plate; but in tie-plates in which these tie-plates are narrower than the tie and the flanges are to be forced into the fibers thereof said flanges are sufficiently shorter than the tie-plate, as illustrated in Fig. 5, to enable the plate proper to project sufficiently beyond the flanges to cover and isolate from moisture the fibers broken down and crushed by the forcing of the flanges into the body of the tie. To further and more effectually isolate from moisture the fibers broken down by the flanges, said flanges 3 may be in the nature of ribs—that is to say, inset so that the sides of the tie-plate will project outwardly beyond them; but whether so inset or not and whether or not the side flanges are to be forced into the face of the tie, as illustrated in Fig. 5, or overlap the sides of the tie I also preferably provide the under surface of the tie-plate with a rib 4 parallel with and intermediate of said side flanges, which rib 4 is adapted to be depressed into the fibers of the tie and terminate at a point inwardly removed from the ends of the tie-plate and a sufficient distance therefrom to enable the tie-plate to entirely cover and isolate from moisture the fibers broken down in forcing the rib 4 into the tie.

By having the rib and the flanges shorter than the tie-plate their resistance when forced into the fibers of the tie to the lateral movement of the tie-plate is not only practically as great as when they are extended to the ends of the tie-plate, but the length of time they may so resist this lateral movement is

substantially increased, for the reason that by the exclusion of moisture from the broken-down fibers they are prevented from softening and finally rotting, and thereby destroying their necessary resistance to the lateral movement of the plate. In other words, by isolating from moisture the fibers necessarily broken down by the ribs and flanges of the tie-plate they will not deteriorate nor the tie-plate loosen until the entire body of the tie is so nearly worn out that its reversal and the shifting of the tie-plate will not be justified.

As shown in the drawings, the rib 4 is triangular in cross-section, as obviously the form of the rib and also the flanges 3 when forced into the fibers of the wood is immaterial, excepting so far as this forcing may be facilitated, and it is within my invention to form the flanges and also the ribs in short and separated sections or in the nature of a series of teeth or points, if so desired. When the width of the tie-plate is such that the side flanges 3 embrace the outer sides of the tie, said flanges may be curved or inclined, as indicated in Fig. 3, and forced to their operative position on the tie after first slipping the plate on the end of the tie, or, if desired, said flanges may be of sufficient distance apart to provide for "dropping the plate," so to speak, into place and afterward bending and forcing the points of the flange tightly against and even into the sides of the tie. On the other hand, the flanges 3 may be straight, as indicated in Fig. 4, or but slightly inclined, so as to be forced downwardly into their operative position, as indicated by the construction shown in Fig. 4. The tie-plate is provided with the usual, preferably square, perforations 5, through which the spikes 6 are driven into the tie for holding both the rail and the tie-plate in their operative position and against moving or creeping longitudinally of the tie; but in order to relieve the body of the spikes 6 as much as possible from the pressure due to the lateral movement of the rails and increase the effectiveness of the spikes for resisting the movement of the tie-plates both laterally and longitudinally of the tie the plates embodying my invention are provided on their upper surface with ribs or other projections forming stops or shoulders 7, against which the outer edge of the base or flange 8 abuts when the tie-plate, the rail, and the spikes are in their operative position, which stops are so constructed and arranged as to substantially, if not entirely, relieve the body of the spike from any lateral contact with the rail-flange, while at the same time the head of the spike fully performs its function of holding the rail down upon the tie-plate and the tie-plate upon the tie, and therefore against vertical movement. To

these ends the stops 7 have their operative faces in a line with and may be in advance of the side walls of the perforations which are parallel with and adjacent the rail-flange, so that the lateral bearing of the rail-flange is substantially against the stops and not against the spike, or, in other words, so that the stops to the substantial exclusion of the spikes resist the lateral movement and pounding of the rail, and to these ends the stop or stops 7 may be of any desired form and arrangement—that is to say, may consist of raised rib-like projections extending entirely across the tie-plate, but sectioned by the spike-perforations in the plate, or such stop may consist of a single enlarged lug or bar or a series of bars at a right angle to and projecting against the edge of the rail-flange, for my invention broadly includes any stop device on the upper surface of a tie-plate, however formed or arranged, forming a bearing for the rail-flange or its web and by which the spikes employed for maintaining the rail and tie-plate from vertical movement are relieved or substantially relieved from the lateral pressure or pounding of the rail.

It is again proper to observe, as before indicated, that in the "shortening," so to speak, of the flanges and ribs on the under side of the tie-plate for the purpose of excluding moisture tending to rot the fibers broken down by the ribs my invention extends to and includes side flanges of the tie-plate, whether one or both embrace the outer sides of the tie, and also a similar tie-plate narrower than the width of the tie on which it is placed.

Having thus described my invention, what I claim as new therein, and desire to secure by Letters Patent, is—

A tie-plate provided with flanges projecting downwardly and inwardly over upon and closely embracing the tie upon which it is used and having ribs provided with cutting edges on its under face at a point intermediate said flanges, said ribs terminating at points inwardly removed from both ends of the tie-plate, said tie-plate being also provided with spike-holes and having on its upper face a transverse rib or ribs, the bases of which project inwardly beyond the inner walls of the spike-holes, whereby a tie-plate closely embraces both sides of a tie, moisture is excluded from the broken-down fibers thereof and the lateral thrust of the rail is removed from the spikes and sustained by the tie-plate, substantially as described.

JULIUS T. DE SOUCHET.
